DESIGN.
—o—
C. E. HAVILAND.
COVER DISH.

No. 21,687.

Fig. 1. Patented July 5, 1892.

UNITED STATES PATENT OFFICE.

CHARLES EDWARD HAVILAND, OF LIMOGES, FRANCE.

DESIGN FOR A COVER-DISH.

SPECIFICATION forming part of Design No. 21,687, dated July 5, 1892.

Application filed June 7, 1892. Serial No. 435,898. Term of patent 14 years.

To all whom it may concern:

Be it known that I, CHARLES EDWARD HAVILAND, a citizen of the United States, residing at the city of Limoges, in the Republic of France, have invented and produced a new and original Design for a Cover-Dish and other Articles, of which the following is a specification, reference being had to the accompanying drawings, forming a part thereof, 10 and in which—

Figure 1 is a top view of a cover-dish bearing my design; Fig. 2, a top view of same with the cover removed; Fig. 3, a side view of same with the cover in position; Fig. 4, an enlarged 15 top view of the handle on said cover; Fig. 5, an enlarged bottom view of the handle on the end of the body of the dish; and Fig. 6 is a detached section through one end of said dish on the dotted line 6 6 of Fig. 2.
20 The leading features of my design consist of the ornamental form and configuration of the dish and its cover and the ornamental handle on the said cover, substantially as shown in the drawings.
25 The cover A is raised at the center and thence inclines toward the edge thereof, which edge is composed of the enlarged scallops B, connected by the short scallops C. The cover A is elongated in form, and in this respect it

harmonizes with the general form of the body 30 D of the dish. The upper edge of the body D is encompassed by a band consisting of the enlarged scallops F and intermediate short scallops G, which conform with the scallops B C on the cover, and below the said band the 35 body D is composed of the scalloped sections H I, which swell outward from the scallops B C and then taper downward and inward to the ornamental base J, as shown in Figs. 3 and 6.

The ends of the body of the dish have the ornate ribbon-scroll handles K, bearing foliate sprays L.

Upon the raised center of the cover A is the ornamental ribbon-scroll handle M, bearing 45 the foliate spray N, as shown in Figs. 1 and 4.

What I claim is—

1. The design for a cover-dish and other articles, substantially as shown and described.
2. In the design for the cover of the dish, 50 the handle, substantially as shown and described.

Signed at the city of Limoges, in the Republic of France, this 25th day of May, 1892.

CHARLES EDWARD HAVILAND.
